UNITED STATES PATENT OFFICE.

ALEXANDER A. ANZELL, OF NEW YORK, N. Y.

DESIGN FOR A SURGICAL MIRROR.

58,533.

Specification for Design.

Patented Aug. 2, 1921.

Application filed September 26, 1919. Serial No. 326,695. Term of patent 14 years.

To all whom it may concern:

Be it known that I, ALEXANDER A. ANZELL, a citizen of the United States, residing in New York, in the county of New York and State of New York, have invented a new, original, and ornamental Design for a Surgical Mirror, of which the following is a specification, reference being had to the accompanying drawing, forming part thereof, in which—

Fig. 2 is a front view of the same.

Fig. 3 is a plan view of Fig. 2.

I claim:

The ornamental design for a surgical mirror, as shown.

ALEXANDER A. ANZELL.
